UNITED STATES PATENT OFFICE.

MAX BROCK, OF NEW YORK, N. Y., ASSIGNOR TO I. B. KLEINERT RUBBER COMPANY,
OF NEW YORK, N. Y., A CORPORATION OF NEW YORK.

POWDER PUFF AND COVER THEREFOR.

Application filed January 6, 1923. Serial No. 611,124.

To all whom it may concern:

Be it known that I, MAX BROCK, a citizen of the United States, and a resident of the city, county, and State of New York, have 5 invented a certain new and useful Improvement in Powder Puffs and Covers Therefor, of which the following is a specification.

This invention relates to an improvement in powder puffs and a combined cover or 10 casing for the same in which the powder puff is contained when not in use and whereby the powder applying surfaces are not exposed and liable to become soiled.

A further object of this invention is to 15 provide a powder puff and case with which several kinds of powder may be applied and by means of which the powder applying portions of the device are kept covered and clean and sanitary at all times.

20 With these objects and other objects which may hereinafter appear, in view, I have devised the particular arrangement of parts hereinafter set forth and more particularly pointed out in the claims appended hereto.

25 Reference is to be had to the accompanying drawing forming a part hereof in which

Figure 1 is a plan view of my improved powder puff and case therefor.

Figure 2 is a sectional view on the line 30 2—2 of Figure 1 looking in the direction of the arrows.

Figure 3 is a plan view of the powder puff and case showing a portion of the puff removed from its pocket in preparation for 35 use, and

Figure 4 is a side elevation showing one manner in which the powder puff may be used.

Throughout the various views of the 40 drawings similar reference characters designate similar parts.

In the preferred embodiment of my invention as disclosed in the accompanying drawing, 1 indicates the back or bottom 45 section of the case which is shown herein as being substantially circular in shape but which may be of any suitable outline to accommodate the form of puff used.

The back 1 of the case is provided with a 50 pair of spaced-apart pockets 2 and 3 which are secured to the back about its edges by means of narrow stitching 4. The edges of the pockets 2 and 3 are also reinforced by similar stitching as shown at 5 and 6.

55 It will be noted that the pockets are

spaced apart leaving a central open section 7 which exposes a portion of the powder puff. The powder puff shown herein consists of two flat sections of material 8 and 9 between which lie two folded sections of 60 pile fabric 10 and 11 which receive the powder and form the powder applying surfaces.

The puff is secured within the casing at a point intermediate of the pockets 2 and 3 65 and within the area 7 by means of stitching 12 and 13 which passes through two outer sections 8 and 9 of the puff and through the back 1 of the case.

From the foregoing it will be apparent 70 that the puff is provided with two powder applying surfaces, one of which consists of the section of absorbent material 10 and the other consists of the section 11. One of these may be used for the application of rouge and the other for the application of powder if desired.

75 To use the desired powder applying surface, it is simply removed from the pocket in which it is stored and spread out flat as is disclosed in Figures 3 and 4. When the act of applying powder has been completed, the surface 10 or 11 as the case may be is folded transversely and replaced within its 80 pocket in the position shown in Figures 1 and 2.

85 To permit easy handling of the device, a suitable ribbon or tape 14 is provided which extends around the back of the case.

90 From the foregoing it is obvious that my invention is not to be restricted to the exact embodiment shown but is broad enough to cover all structures coming within the scope of the annexed claims.

95 What I claim is:

1. An article of the class described comprising a case having a pair of pockets, a powder puff secured in said case and having a pair of powder-applying surfaces one of each of which is normally held in each of 100 said pockets.

105 2. An article of the class described comprising a case having a pair of spaced pockets, a powder puff having a pair of powder-applying surfaces folded upon themselves with one of each of said powder-applying surfaces contained in each of said pockets.

110 3. An article of the class described comprising a powder puff having a pair of powder-applying surfaces folded upon them-

selves and normally extending in opposite directions, a case secured to said puff between said powder-applying surfaces, and a pair of pockets on said case for enclosing 5 said powder-applying surfaces.

4. An article of the class described comprising a powder puff case having a back, a pair of spaced pockets extending from one face thereof, a powder puff secured to said 10 case at a point between the pockets, and a pair of powder-applying sections on said puff extending into said pockets.

5. An article of the class described comprising a powder-puff case having a back, a 15 pair of spaced pockets secured to the edge of said back and extending from one face thereof, a powder puff secured to the back

of said case at a point between the pockets, and a pair of powder-applying sections folded in half and fitting into said pockets 20 and independently removable from said pockets.

6. An article of the class described comprising a powder puff case having a pair of spaced pockets, a puff held within said case 25 said puff having a pair of powder-applying sections held in folded position within said pockets and adapted to be unfolded and spread out flat when removed from said pockets.

Signed at the city, county and State of New York, this 27th day of December, 1922.

MAX BROCK.
